UNITED STATES PATENT OFFICE.

WILLIAM C. KISNER, OF WATSON, WEST VIRGINIA.

WRENCH.

Application filed May 8, 1925. Serial No. 28,807.

This invention relates broadly to wrenches, and more specifically to a wrench of ratchet type.

The primary object of the invention is to provide a wrench having a relatively adjustable jaw structure and having one of its jaws shiftable away from the opposite jaw under the force which is exerted thereon in returning the wrench to an initial position for obtaining a new hold.

A further object is to provide a simple and practical wrench which functions in the manner of ordinary forms of ratchet wrenches and which, at the same time, is adjustable to accommodate itself to nuts of different sizes.

In describing the invention in detail, reference is herein had to the accompanying drawings, in which—

Figure 1 is a side elevation of a wrench constructed in accordance with my invention; the same being shown in rotating relation to a nut;

Figure 2 is a similar view showing the wrench being reversed over the nut to obtain a new hold; and—

Figure 3 is a section taken substantially on line 3—3, Fig. 2.

Referring to said drawings, 1 indicates the wrench head which is pivotally mounted upon a tongue 2 of reduced thickness formed on the front end portion of a wrench handle 3, said head having in its rear end a recess or transverse slot 4 within which said tongue 2 is received. Said wrench head 1, which is of materially greater width at its front end than at its rear, or pivoted, end, has extending therethrough adjacent to its said front end a transverse bore or way 5 which opens outward through the face of said front end in the form of a relatively narrow slot 6.

The bore 5 constitutes a guideway in one end of which is disposed for transverse sliding movement a rack-bar 7 formed upon a movable jaw 8, the teeth of said rack-bar being engaged with a worm 9 which is located within and has opposite portions of its periphery protruding from opposite sides of an opening 10 in said head 1. Said worm is mounted for rotation upon a pin 11 which crosses said opening 10, as shown.

A notched member 12 carried by a second jaw 13 is disposed for sliding movement in the opposite end of the guideway 5, said jaw 13 being located in opposed relation to the adjustable jaw 8. A flat resilient steel spring

14 is disposed with its free end against the outer end of said member 12 for normally holding the jaw 13 in its inwardly-thrust position, shown in Fig. 1. In said position, the point of a pivoted dog 15 is disposed in a notch 16, one or more of which are provided in the member 12, as shown. Said dog has its outer end pivotally mounted in a recess or channel 17 provided therefor in an arm 18 which is fixed to, or formed integral with, the wrench handle 3 and which forms a fixed or movement-limiting abutment against which the adjacent edge portion of the head 1 and the spring 14 normally rests, as shown in Fig. 1. Said head is normally held in seated relation to said arm or abutment by means of a flat resilient steel spring 19 which is attached to the handle 3 and has its free end portion seated against the edge portion of said head opposite that which bears the spring 14.

The dog 15 is longitudinally movable into and out of engagement with the notch 16 through holes 20 and 21 provided therefor in the spring 14 and the head 1, said hole 21 extending at substantially a right angle to the bore 5.

In practice, by rotation of the worm 9, the jaw 8 is adjusted to position it at the proper distance from the normally stationary jaw 13 for grasping the part, as the nut 22, to be rotated, as shown in Fig. 1. The wrench is then rotated forward in the direction indicated by the arrow in said figure. In such forward rotation the jaw 13 is maintained against movement in an outward direction both by the pin 15 engaged with the notch 16 and by the arm 18 which is then abutted by a portion of said jaw.

Following the advance rotation described, or when the wrench is to be returned to obtain a new hold on the nut, the return movement may be effected without disengaging the wrench from the nut, or in the manner of a ratchet wrench. When the wrench handle 3 is so returned in the direction indicated by the arrow in Fig. 2, the force exerted to effect rearward movement of the jaws with respect to the stationary nut 22 acts to produce relative movement between the said handle and the head 1, the former turning on the connecting pivot pin 23 against the pressure exerted by the spring 19, so that the said parts occupy approximately the relative positions shown in said figure. Additionally, as the arm 18 is withdrawn from

abutting relation to the head 1, the point of the dog 15 is withdrawn from engagement with the notch 16, releasing the jaw 13. Said jaw, so released, is then capable of outward movement against the slight pressure exerted by the spring 14 to the extent that it may abut the arm 18 in the then withdrawn position of the latter. The outward movement of the jaw 13 is induced as the latter passes over the angular edges of the then stationary nut in the rearward rotary movement of the wrench, as shown in Fig. 2. The spring 14 acts to return said jaw to its normal position following the passage of the latter over said angular edges. When the wrench comes to rest following the rearward movement thereof, the parts resume their normal positions shown in Fig. 1.

What is claimed is—

- 20 1. A wrench comprising a handle, a head attached pivotally to said handle to permit relative lateral movement, an arm carried by said handle in a position to limit the extent of said movement in one direction, resilient means normally holding said head in abutting relation to said arm, a jaw mounted on said head and shiftably transversely of the latter, a dog for normally holding said jaw stationary, said dog being pivotally mounted on said arm and said head having therein an opening through which said dog is movable into and out of holding relation to said jaw with movements of said head away from and to-

ward said arm, a second jaw carried by said head in opposing relation to the first mentioned jaw, a rack-bar formed integral with said second jaw, said head having a transverse guideway in which said rack bar is slideable and an adjusting worm engaged with said rack-bar. 35

2. A wrench comprising a handle, a head attached pivotally to said handle to permit relative lateral movement, an arm carried by said handle in a position to limit the extent of said movement in one direction, resilient means normally holding said head in abutting relation to said arm, a jaw mounted on 40 said head and shiftably transversely of the latter, a dog for normally holding said jaw stationary, said dog being pivotally mounted on said arm and said head having therein an opening through which said dog is movable into and out of holding relation to said jaw with movements of said head away from and toward said arm, a spring normally tending to hold said jaw in an inwardly thrust position, a second jaw shiftably mounted on said head, and means for adjusting said second jaw relative to the first mentioned jaw. 45 50 55

In testimony whereof, I affix my signature.

WILLIAM C. KISNER.
